US00D630340S

(12) **United States Design Patent**
Southwell

(10) **Patent No.:** **US D630,340 S**
(45) **Date of Patent:** **** *Jan. 4, 2011**

(54) **BUILDING ELEMENT**

(75) Inventor: **Darren Southwell**, Bella Vista (AU)

(73) Assignee: **James Hardie Technology Limited**,
Dublin (IE)

(*) Notice: This patent is subject to a terminal disclaimer.

(**) Term: **14 Years**

(21) Appl. No.: **29/351,068**

(22) Filed: **Nov. 30, 2009**

(30) **Foreign Application Priority Data**

May 29, 2009 (AU) 12006/2009

(51) LOC (9) Cl. **25-01**

(52) U.S. Cl. **D25/122**; D25/123

(58) **Field of Classification Search** D25/119,
D25/123, 102, 122; 52/272, 273, 276, 255,
52/287.1

(57) **CLAIM**

The ornamental design for a building element, as shown and described.

DESCRIPTION

FIG. 1 is a first perspective view of a building element;

FIG. 2 is a first end view of the building element shown in FIG. 1;

FIG. 3 is a first side view of the building element shown in FIG. 1;

FIG. 4 is a plan view of the building element shown in FIG. 1;

FIG. 5 is a second side view of the building element shown in FIG. 1;

FIG. 6 is a second end view of the building element shown in FIG. 1;

FIG. 7 is a bottom view of the building element shown in FIG. 1; and,

FIG. 8 is a second perspective view of a building element shown in FIG. 1.
